UNITED STATES PATENT OFFICE

GEORGE W. GREBENSTEIN, OF NEWTONVILLE, MASSACHUSETTS

TIRE TOOL

Application filed October 18, 1929. Serial No. 400,506.

In the course of the development of rims for the mounting of tires for automobiles certain types of so-called split rims have become more or less standard so that garages and service stations are called on to handle such rims frequently in mounting and demounting tires.

While the rim type has become settled as a type, the latches have not and a separate tool to operate each special latch has been required. This has been a great inconvenience to garage and service men and in the confusion of a multiplicity of tools make-shift instruments were used frequently simply because no one tool would meet all requirements.

To the end of providing in a single tool means for performing various operations including the actuation of various styles of rim latches, my invention contemplates a tool of lever type and useful for various uses as such including an arm extension by reason of which it becomes a latch operating lever for the two predominant types of split rim latches.

The tool shown in the accompanying drawing is characteristic and while capable of some variation in design is advantageous in simplicity and general adaptability. In the drawing:

Fig. 1 is a side elevation of the tool mentioned.

Fig. 2 is a view at right angles.

Fig. 3 is an end view.

Fig. 4 is a view of the tool in use on one type of link.

Fig. 5 a similar view illustrating its use with another type, and

Fig. 6 a view illustrating its use with still another link.

As shown in the drawing, the tool comprises an elongated handle or lever member 1. This is preferably flattened out as at 2, thus forming a flat hand bearing and tire blade for freeing the bead of a shoe or like uses.

At its opposite end the handle member 1 is turned in approximately a right angle 3 into a lateral arm 4 which is so constructed as generally to produce a diagonal half twist as indicated at 4'. The portion of this lateral arm joining the lever 1 is generally circular in

cross section but the material on the upper face thereof is cut away diagonally as shown in Figs. 1 and 3. Beyond this portion 4' is a flattened and widened portion 4² which is provided with an aperture 5 which is preferably squared or other annular opening. Beyond this opening the arm 4 terminates in a squared or angled point 6. The cut-away portion of 4' merges with one wall of the flattened portion 4² so that when the point 6 is inserted in a link on a rim the twist in the member 4 tends to provide clearance of the tire by the lever member 1, and the enlarged portion 4² constitutes a limiting stop to limit the insertion of the bill 6 into the aperture of the rim lock.

The arm 4 is slightly offset from the plane of the member 1 and the combination of the relation of the angle of that offset and the angle of the twist in the arm 4 provide ample clearance of the tire regardless of the operation or position of the tool.

Beyond this the arm 4 terminates in a squared or angled point 6.

The lever 1 with its flattened end 2 is useful in too many ways to permit of enumeration, but is generally adapted to all lever, pinch bar, wedging and like uses. It also constitutes a broad blade screw driver for which the elbow arm 4 constitutes a crank, the aperture 5 being useable for the insertion of a handle if desired.

The special uses, however, relate to split rim operations in which an expanding and collapsing link is present. As shown in Fig. 4, the tool is shown with its terminal bill or beak 6 inserted in the tool aperture of a link L on a rim R.

In Fig. 5 the aperture 5 is shown slipped over the ends of the link L¹ to operate the split rim R, while in Fig. 6 a device is shown with a different type link L² similar to that of Fig. 4.

The tool shown is extremely simple and inexpensive and has a very wide range of uses. Regardless of the type of latch with which the tool is used, its offset arm 4 ensures clearance of the tire which has been impossible in structures heretofore known.

What I therefore claim and desire to secure by Letters Patent is:

1. A tool for operating a link connected split rim comprising a bar having a straight lever portion and a bent and twisted end extension thereof, which has a socket transversely thereof, the axis of which socket is inclined relative to said lever portion so that when the socket is engaged with the link, the lever will be laterally spaced from the rim.
2. A tool for operating the link of a link connected split rim comprising a lever portion having a lateral end extension, said extension being disposed at an obtuse angle to the lever portion whereby the latter is disposed outwardly of the plane of the rim when the lateral end extension is operatively engaged with the link, said lateral end extension having a link engaging formation disposed transversely thereof, the longitudinal axis of said formation being disposed transversely of said extension and at an acute angle to a plane including the longitudinal axes of the lever and the lateral end extension whereby the lever is disposed within the circumferential limits of the rim when the said link engaging formation is operatively engaged with the link.
3. A tool for operating the link of a link connected split rim comprising a lever portion having a lateral end extension, said extension being disposed at an obtuse angle to the lever portion whereby the latter is disposed outwardly of the plane of the rim when the lateral end extension is operatively engaged with the link, said lateral end extension having a link engaging socket disposed transversely thereof, the longitudinal axis of said socket being disposed transversely of said extension and at an acute angle to a plane including the longitudinal axes of the lever and the lateral end extension whereby the lever is disposed within the circumferential limits of the rim when the said link engaging socket is operatively engaged with the link.
4. A tool for operating the link of a link connected split rim comprising a lever portion having a lateral end extension provided with an enlargement, the enlargement having a socket formed therethrough to receive a part of the link to adapt the tool for opening the link, and a terminal bill formed on said lateral end extension for engagement in an aperture of a link to adapt the tool for opening apertured links, the said enlargement constituting an abutment to limit insertion of the bill into a link aperture.

In testimony whereof I affix my signature.

GEORGE W. GREBENSTEIN.
